(57) **CLAIM**

The ornamental design for a fragrance bottle, as shown and described.

DESCRIPTION

FIG. 1 is a top, front and right side perspective view of a first embodiment of our new design for a fragrance bottle; FIG. 2 is a front elevation view of the fragrance bottle, shown in FIG. 1;

FIG. 3 is a right side elevation view of the fragrance bottle, shown in FIG. 1;

FIG. 4 is a rear elevation view of the fragrance bottle, shown in FIG. 1;

FIG. 5 is a left side elevation view of the fragrance bottle, shown in FIG. 1;

FIG. 6 is a top plan view of the fragrance bottle, shown in FIG. 1;

FIG. 7 is a bottom plan view of the fragrance bottle, shown in FIG. 1;

FIG. 8 is a top, front and right side perspective view of a second embodiment of our new design for a fragrance bottle; FIG. 9 is a front elevation view of the fragrance bottle, shown in FIG. 8;

FIG. 10 is a right side elevation view of the fragrance bottle, shown in FIG. 8;

FIG. 11 is a rear elevation view of the fragrance bottle, shown in FIG. 8;

FIG. 12 is a left side elevation view of the fragrance bottle, shown in FIG. 8;

FIG. 13 is a top plan view of the fragrance bottle, shown in FIG. 8; and,

FIG. 14 is a bottom plan view of the fragrance bottle, shown in FIG. 8.

The broken line showing of a spray nozzle and portions of the base of the bottle in FIGS. 1, 2, 6, 7, 8, 9, 13 and 14, are included for illustrative purposes only and form no part of the claimed design.

1 Claim, 8 Drawing Sheets
